UNITED STATES PATENT OFFICE.

HAROLD E. SWENSON, OF VALLEJO, CALIFORNIA.

ENVELOPE OPENER.

Application filed June 27, 1921. Serial No. 480,761.

To all whom it may concern:

Be it known that I, HAROLD E. SWENSON, a citizen of the United States, residing at Vallejo, in the county of Solano and State of California, have invented new and useful Improvements in Envelope Openers, of which the following is a specification.

This invention relates to paper cutters and more particularly to that class of paper cutters used for opening envelopes.

The object of the present invention is to provide a paper cutter of this class by which envelopes may be quickly opened by cutting off a narrow strip of the edge, the width of this strip being regulated so as to prevent injury to the contents.

Another object is to provide an envelope opener of neat appearance and compact construction so that it may be readily carried from place to place.

A further object is to provide a paper cutter in which the blade is securely protected to enable the device to be carried in the pocket.

With the above objects in view the invention consists of an L-shaped supporting member having a groove formed in its base, a cutting blade pivoted to an extension of the supporting member, a lug mounted on the cutting blade and extending below the edge of the same in order to prevent the blade from coming in contact with the bottom of the groove, and a spring normally maintaining the blade in an elevated position.

In the drawings:—

Figure 1 represents an elevation of an envelope opener constructed in accordance with my invention;

Figure 2 is an enlarged sectional elevation of the pivot end of the blade, this section being taken through the groove of the base; and

Figure 3 is a transverse section of the same.

In constructing the improved paper cutter there is provided a supporting base of substantially L-shaped cross section, the vertical member of this supporting base being designated by the numeral 1. The base portion of the supporting member is designated at 2 and is provided with a longitudinal groove 3 in its upper surface which has a slot 3' formed in one wall thereof for the

purpose of permitting the strip cut from the envelope to pass therethrough. An extension 4 at one end of the base provides means for supporting a lug 5, and this lug and in a line with the groove 3, is pivoted as at 6 for a cutting blade 7. This blade is provided with a cutting edge 8 upon its lower side, and this cutting edge is adapted to operate in a groove 3.

Means are provided for preventing the cutting edge 8 from contact with the bottom of the groove 3 and thereby causing the said edge to become dull. This means consists of a lug 9 preferably formed on the blade 7 and as shown is adapted to engage the base of the supporting member before the edge 70 of the blade reaches the bottom of the groove 3. This allows the blade to perform the function of cutting a strip from the envelope and at the same time preventing the cutting edge becoming dull by contact with the groove. Mounted upon the upper edge of the blade 7 is an operating member 10, which is located at a point just in advance of the pivot 6. As the blade is pivoted to the extension 4 of the supporting member and the operating member 10 is located just in advance of this pivot ample room is provided for gripping or striking the operating handle of the blade in its operation. By reference to the drawings this will be apparent as the portion 1 of the supporting member terminates in advance of the member 10. Located preferably directly beneath the operating member is a spring 11 and this spring is interposed between the blade and the extension of the supporting member and serves to normally maintain the blade in an elevated position.

The construction of the improved opener is such that it requires very little space for packing, the cross sectional area being very thin.

From the foregoing it will be seen that the invention provides a very simple and efficient envelope opener which is attractive in appearance and durable of construction. As before stated the lug 9 prevents the blade 7 from becoming dulled so that the usefulness of the device is greatly enhanced.

Various changes in the form and proportions of the invention may be made as may fall within the scope of the appended claim.

Having described the invention what I de-

sire to claim and secure by Letters Patent, is:—

A paper cutter comprising a substantially L-shaped member including a base and a vertically disposed wall rising from the base, said base having a groove at its upper face at the juncture with the side wall and said side wall having a slot adjacent the

lower end and opening into the groove, a spring elevated blade pivotally mounted upon the L-shaped member and operating within the groove and an operating handle for the blade. 10

In testimony whereof I affix my signature.

HAROLD E. SWENSON.
